UNITED STATES PATENT OFFICE.

JOSEPH A. FREUND, OF NEWTONVILLE, MASSACHUSETTS, ASSIGNOR TO KEYSTONE WATCH CASE COMPANY, OF PHILADELPHIA, PENNSYLVANIA, A CORPORATION OF PENNSYLVANIA.

STEM WINDING AND SETTING DEVICE.

1,378,408.

Specification of Letters Patent. Patented May 17, 1921.

Application filed July 5, 1918. Serial No. 243,299.

To all whom it may concern:

Be it known that I, JOSEPH A. FREUND, a citizen of the United States, and resident of Newtonville, county of Middlesex, Massachusetts, have made a certain new and useful Invention Relating to Stem Winding and Setting Devices, of which the following is a specification, taken in connection with the accompanying drawing, which 10 forms part of the same.

This invention relates especially to stem winding and setting devices for watches in which the pendant lever has a rigidly connected pivot stud which is preferably mounted in a pivot bearing in the dial plate in which the winding stem is supported. A retaining spring which may advantageously engage the pendant lever between its pivot pin and the actuating lug thereon normally 15 presses this pivot pin into its bearing hole and simultaneously holds the actuating stud in engagement with the actuating groove in the winding stem. At the same time, however, the pivot stud may be engaged by a 20 pin or other device inserted in the pivot bearing hole in the other side of the watch so that pressure on the pivot stud may force it and the connected pendant lever away from the dial plate so as to carry the actuating lug 25 out of the groove in the winding stem and allow the removal thereof. In this way an amply long strong bearing is secured on this pendant lever so that it is unlikely to be loosened or broken under severe 30 service and it is yieldably and reliably held in operating position in which it co-operates with the clutch lever while pressure on the countersunk pivot stud may instantly release the winding stem when desired.

40 In the accompanying drawing showing in a somewhat diagrammatic way an illustrative embodiment of the invention—

Figure 1 is a front view showing the stem winding and setting mechanism.

45 Fig. 2 is a transverse section thereof taken substantially through the pendant lever; and

Fig. 3 is a similar view showing the parts in released position.

50 The dial plate 1 is preferably made of thick heavy construction adjacent the winding stem so that the winding stem 3 may be mounted wholly within the dial plate and the co-operating stem bushing 25. In this 55 way a firm and secure bearing is provided

for the winding stem which promotes the accurate and reliable operation of the other parts. The pendant lever 12 is preferably rigidly and permanently connected to its pivot stud 13 which may have the reduced 60 end 27 riveted or otherwise secured in a hole in the pendant lever as indicated in Fig. 2 and this pivot stud is of such length as to extend substantially through the dial plate and co-operating bridge member 26 which 65 is preferably relatively thin adjacent the winding stem, the end of this pivot stud being preferably though not necessarily slightly countersunk to prevent its accidental displacement. The pendant lever may, 70 if desired, be mounted within a suitable recess 2 in the dial plate which also accommodates the retaining spring 21 securely held at one end by a mounting formed of the spring screw 20 and washer 29. In this way 75 the free end of this spring may engage the pendant lever between its pivot stud and the actuating lug 15 which may be integral therewith and which is adapted to engage the actuating groove 24 in the winding stem 80 by which the pendant lever is oscillated when the winding stem is strongly pulled outward in the usual way.

The co-operating clutch lever 18 may have 85 its end located within the annular groove or recess 8 in the clutch sleeve 6 which is mounted on the squared or polygonal portion 10 of the winding stem and formed with a correspondingly shaped hole so that it rotates with the stem. This clutch lever may 90 be conveniently mounted about the pin or screw 19 in the dial plate and is normally held in the raised position indicated in Fig. 1 by a suitable spring, such as the clutch spring 22 which may be held at its other 95 end by an anchor screw 23. This clutch lever may have an angular or upwardly extending portion 17 co-operating with the adjacent part 14 of the pendant lever so as to be operated thereby, the position or shape 100 of these engaging portions being such as to insure this operation as by the use of a suitable wedging operating face 16 on the clutch lever.

In the raised position indicated the clutch 105 lever holds the clutch sleeve 6 up in engagement with the clutch member 5 on the winding pinion 4 so that when the winding stem is rotated this winding pinion is rotated in unison therewith and operates the winding 110

wheels of the watch. When, however, the winding stem is drawn outward, the pendant lever 12 is correspondingly oscillated about its pivot stud 13 and this forces the 5 clutch lever 18 downward against the action of its spring 22 so as to disengage the clutch members connecting this sleeve with the winding pinion and also simultaneously throw the crown setting gear 7 into mesh 10 with the setting pinion 9. Under these conditions the rotation of the winding stem rotates the setting pinion and connected setting wheels so as to set the hands of the watch after which the winding stem may be 15 forced inward to restore the parts to their Fig. 1 position.

By giving the pendant lever a long bearing pivot stud seated in the dial plate in which the winding stem is mounted, its 20 rigidity and strength are promoted to an important degree and its effective operating alinement with the other parts can be insured in spite of the severe strains to which the winding stem often subjects it. Furthermore, when the watch is to be taken 25 apart a pin or tool, such as 28, may be forced against the somewhat countersunk end of the pivot stud as shown in Fig. 3 so as to push this stud and the connected pendant lever out away from the dial plate and the winding stem 3, thus disengaging the actuating lug from the stem recess and allowing the winding stem to be instantly withdrawn. When released the pendant lever 30 is forced back into place by its retaining spring and this yielding mounting also allows the winding stem to be forced into place, the different cylindrical and polygonal parts of the stem readily working past the actuating lug on the pendant lever so that it is usually unnecessary to otherwise release the pendant lever or lug in the manner indicated 35 in Fig. 3.

This invention has been described in connection with a number of illustrative embodiments, forms, proportions, parts, materials and arrangements, to the details of which disclosure the invention is not of course to be limited, since what is claimed 45 as new and what is desired to be secured by Letters Patent is set forth in the appended claims:

1. The stem winding and setting devices for watches comprising a dial plate and co-operating relatively thin bridge member adjacent the stem bearing, a winding stem mounted entirely within said dial plate, a winding pinion and clutch sleeve loosely mounted on said winding stem, a clutch 50

lever coöperating with an annular recess in 60 said clutch sleeve, a pendant lever mounted in a recess in said dial plate and having an integral actuating lug coöperating with the actuating groove in said winding stem and having a rigidly connected pivot stud 65 mounted in a bearing hole in said dial plate and coöperating bridge member so that its free end is slightly countersunk and having an operating end coöperating with said clutch lever and a retaining spring mounted 70 in said recess and engaging said pendant lever between its pivot stud and actuating lug to releasably hold it in coöperation with said winding stem.

2. The stem winding and setting devices 75 for watches comprising a dial plate and co-operating relatively thin bridge member adjacent the stem bearing, a winding stem mounted within said dial plate, a clutch sleeve loosely mounted on said winding 80 stem, a clutch lever coöperating with said clutch sleeve, a pendant lever mounted in a recess in said dial plate and having an actuating lug coöperating with the actuating groove in said winding stem and having a 85 rigidly connected pivot stud mounted in a bearing hole in said dial plate and having an operating end coöperating with said clutch lever and a retaining spring mounted in said recess and coöperating with said 90 pendant lever to releasably hold it in coöperation with said winding stem.

3. The stem winding and setting devices 95 for watches, comprising a plate, a winding stem, a clutch sleeve mounted on said winding stem, a clutch member coöperating with said clutch sleeve, a pendant lever operating said clutch member and pivotally mounted on said plate and having an actuating lug coöperating with said winding stem and a 100 retaining spring engaging said pendant lever between its pivot point and actuating lug to releasably hold it in coöperation with said winding stem.

4. The stem winding and setting devices 105 for watches comprising a plate, a winding stem, a pendant lever mounted on said plate and having an actuating lug coöperating with said winding stem and having a rigidly connected pivot mounted in said plate 110 so that its free end is normally countersunk below the adjacent member and a retaining spring engaging said pendant lever between its pivot and actuating lug to releasably hold it in coöperation with said winding 115 stem.

JOSEPH A. FREUND.
